UNITED STATES PATENT OFFICE.

SALTON McGIBBON, OF EDMONTON, ALBERTA, CANADA.

SAFETY-PIN.

1,323,886.

Specification of Letters Patent.

Patented Dec. 2, 1919.

Application filed February 16, 1918. Serial No. 217,725.

To all whom it may concern:

Be it known that I, SALTON McGIBBON, a subject of the King of Great Britain, residing at Edmonton, in the Province of Alberta and Dominion of Canada, have invented new and useful Improvements in Safety-Pins, of which the following is a specification.

This invention relates to fastening devices especially adapted for securing lap robes and the like to the robe rails or other convenient parts of a vehicle, in order to prevent their unauthorized removal.

To this end the invention comprehends the provision of a pin adapted to be passed through the robe after the latter has been folded around the robe rail, the pin being so formed as to provide for the passage of a lock shackle to prevent its removal by unauthorized persons.

For the accomplishment of the above, the pin includes a substantially semi-circular resilient body portion, having its ends connected by the pin proper, the latter having one end connected to the body portion by a coiled spring, while the opposite end of the pin is bent at a substantial right angle for engagement between loops provided at the adjacent end of the body portion, where it is secured by the passage of the lock shackle through the loops with the extremity of the pin within an additional loop provided upon said body portion adjacent the first mentioned loops.

35 In the drawings:

Figure 1 is a sectional view through a robe rail or rod with a robe secured thereto by means of the improved fastening device.

Fig. 2 is a side elevation of the pin removed from the rod, the extremity of the pin being in position prior to its final adjustment for the reception of the lock.

Fig. 3 is an edge view of the pin in its closed position with the lock removed, and

45 Fig. 4 is a detailed sectional view on the line 4—4 of Fig. 1 looking in the direction of the arrow.

Referring to the drawings in detail, wherein like characters of reference denote corresponding parts, there is illustrated at R a rail, which may be the robe rail of a vehicle and which has secured thereon a lap robe L. The robe is folded upon the rail in the manner shown in Fig. 1 and is secured thereon by the passage of the pin through

such folded end and the body portion of the robe, the pin being designated in its entirety by the reference character 10.

The pin 10 includes a body portion 11, which is preferably semi-circular in cross section so as to engage over the rail R, one of the extremities of the body portion having formed thereon a coiled spring 12, by means of which it is connected to one end of the pin proper 13, the latter being preferably formed integral with the spring and body portion 11 of the pin. The opposite extremity of the body portion 11 is bent to provide loops 14, which are disposed substantially in the same plane as to said body portion, the material of which the pin is formed being bent around the adjacent portion of the body portion to provide a substantially right angular loop 15. The pin 13 has its extremity bent into a substantially right angular portion and passed between the loops 14 and through the loop 15 and lying substantially parallel to the body portion 11.

For the purpose of preventing the unauthorized removal of the pin 13, there is employed a lock 17, which may be in the form of a Yale or combination lock having its shackle passed through the loops 14 and around the right angled portion 16 of the pin 13. The pin will be thus securely held between the loops 14, the engagement of the lock preventing the necessary lateral movement of the right angled portion 16 with respect to the body portion for the removal of the pin. This movement is clearly shown in Fig. 2 of the drawings.

The pin is susceptible of various other uses than the manner shown and described and the right is reserved to make any changes in its form and proportions as will properly fall within the scope of the appended claims.

Having described the invention, what is claimed is:

1. A fastening device formed of a single strand of spring wire and embodying a substantially semi-circular body portion, a penetrating member having one end connected to one end of the body portion, means provided at opposite ends of said body member to receive the pin and means included in the pin receiving means for the reception of a lock to prevent the removal of the pin.

110

2. A fastening device formed of a single strand of spring wire and embodying a substantially semi-circular body portion, a penetrating member having one end connected to one end of the body portion, spaced loops provided at the opposite end of the body portion to receive the penetrating member and a lock engageable with said loop and member to prevent the removal of the latter.

3. A fastening device formed of a single strand of spring wire and embodying a substantially semi-circular body portion, a penetrating member having one end connected to one end of the body portion, spaced loops provided at the opposite end of said body portion, a substantially right angled extremity formed on said penetrat-

ing member for engagement between the loops and a lock engageable within said loops and right angled extremity to prevent the removal of the latter.

4. A fastening device formed of a single strand of spring wire and embodying a substantially semi-circular body portion, a penetrating member having one end connected to one end of the body portion, spaced loops crossed at one edge to receive and provide a stop for the opposite end of the penetrating member and means engageable through said loops and around the penetrating member to prevent removal of the latter.

In testimony whereof I affix my signature.

SALTON McGIBBON.
